UNITED STATES PATENT OFFICE.

A. ELIAERS, OF BOSTON, MASSACHUSETTS.

IMPROVED ELASTIC STUD OR BUTTON.

Specification forming part of Letters Patent No. 43,762, dated August 9, 1864.

To all whom it may concern:

Be it known that I, A. ELIAERS, of Boston, in the county of Suffolk and State of Massachusetts, have invented certain new and useful Improvements in Elastic Studs or Buttons; and I do hereby declare that the following description, taken in connection with the accompanying drawings, hereinafter referred to, forms a full and exact specification of the same, wherein I have set forth the nature and principles of my said improvements, by which my invention may be distinguished from all others of a similar class, together with such parts as I claim and desire to have secured to me by Letters Patent.

In and upon various articles—such as chair-legs, canes, crutches, the edges of doors and windows, &c.—elastic studs or thimbles, made of rubber, gutta-percha, and other similar materials, have been used to prevent noise, slipping, and for various other purposes. They have also been applied to lead-pencils for erasers. In the use of these elastic studs or sockets great difficulty has been experienced in retaining them in or upon the articles to which they were applied, and the object of the present invention is to so construct them as to cause them when once attached to bind and hold themselves securely in their proper positions. In cases where the elastic protector is to be applied to the outside of the article—such as chair-legs, crutches, &c.—I form a hollow socket of rubber or gutta-percha, having a projecting rim or shoulder on its inside periphery that will fit into a suitable groove on the outside of the article to which it is applied. When the elastic protector is to be inserted in holes or grooves of unvarying diameter, I form it of a conical, wedge, or other shape, in which one end is larger than the other, so that when sprung into the said straight holes or grooves the binding force exerted by its base will prevent its being

easily disengaged or drawn out therefrom. I also construct an elastic stud or button especially adapted to holes or grooves which are undercut—that is, those which are formed with a shoulder inside. I effect this by making an elastic stud or button with a projecting base, so as to form a lip, which, when the stud or button is sprung in, will bear against the shoulder in the groove or aperture.

In the accompanying drawings, Figure 1 shows my improved protector applied to a chair-leg; Fig. 2, as inserted in an undercut groove, and Fig. 3 as inserted in a straight aperture.

In Fig. 1 *a a* represent a hollow shell of rubber having a projection or shoulder, *b b*, on its inside, so formed that when the said shell is sprung upon the chair-leg *c* it will fit into a groove or depression formed therein for the purpose, and thus hold the elastic protector securely in its place.

In Fig. 2, *d e* represent a stud or button, of rubber or gutta-percha, having its base *e* larger than its upper portion, *d*, and so formed as to make a lip, *f*, which, when the stud or button is sprung into an undercut groove, *g*, will bear against a shoulder, *h*, as will readily be understood.

In Fig. 3, *i i* is a stud or button, whose base is larger than its upper portion, so when forced into a straight hole in aperture *k k* it will hold itself firmly therein.

Having thus described my improvements, I shall state my claim as follows:

Forming an elastic hollow socket with a projecting rim or shoulder on its inside, that fits into a corresponding groove on the outside of the article to be protected, as described.

AT. ELIAERS.
